UNITED STATES PATENT OFFICE.

CHARLES WILLIS WARD, OF YONKERS, NEW YORK.

DESIGN FOR A WATCH-BRIDGE.

SPECIFICATION forming part of Design No. 18,722, dated November 6, 1888.

Application filed September 10, 1888. Serial No. 225,079. Term of patent 7 years.

To all whom it may concern:

Be it known that I, CHARLES WILLIS WARD, a citizen of the United States, residing at Yonkers, in the county of Westchester and State of New York, have invented and produced a new and original Design for a Watch-Bridge; and I do hereby declare the following to be a full, clear, and exact description of the same, reference being had to the accompanying drawing, forming a part thereof.

My invention relates to a new and original design for upper plates or bridge for watches; and it consists in the peculiar formation and ornamental shaping hereinafter described and claimed.

As shown in the accompanying engraving, the outer casing, A, is represented as encircling the works of a watch, the respective bridges abutting against the same and extending inward toward the center. That portion of the bridge or plate designated by B, and commonly known as the "barrel-bridge," is semicircular in form, it extending midway the length of the watch, its outer edge conforming to the inner contour of the casing. The upper edge of this portion B is formed in a series of graceful curves, which extend from opposite sides or corners, bending uniformly downward at increasing inclines to points midway the center and the sides. At this point the edges are curved abruptly upward and unite to form a dome or circular projection, as C, which projects over the center of the watch above the plane of the sides. That portion of the plate commonly known as the "train-bridge," designated by D and located above and at the right of the portion B, has its lower edge curved in a manner diametrically opposite that of the adjacent portion of the lower bridge. The end of portion D is extended in toward the

center and terminates in a rounded or circular point occupying a position between the projection C and the upper curved edge of portion B. The upper or side edge of this portion D is curved inwardly, as shown, there being a circular projection, as A, about midway its length, which breaks its continuity. By forming the lower edge as described and placing the portion D as shown a space is formed between the two bridges which has parallel sides extending from a point near the center to the outer edge of the watch, thus adding to the beauty of the design. The portion E extends downward from the top of the casing, its lower end coming in proximity to the projection d on portion D, its side adjacent to said portion being curved inwardly to form a substantially oblong space between the two. The opposite side of portion E is formed into a graceful curved extension, as shown. The end of the bridge has a knob, in which is placed the bearing for the escapement.

F represents the balance-cock, which is of the usual form and extends into the space between the upper and lower portions. 65

By this design an artistic plate is formed and the ornamental under plate, the balance, and a large portion of the train are visible.

Having thus described my invention, what I claim as new, and desire to secure by Letters Patent, is—

The design for a watch-bridge, substantially as herein shown and described.

In testimony whereof I affix my signature in presence of two witnesses.

CHARLES WILLIS WARD.
